PHONOGRAPH

Heinrich F. Max Gramann, Orange, N. J., assignor to Thomas A. Edison, Incorporated, West Orange, N. J., a corporation of New Jersey

Application July 18, 1933, Serial No. 680,908

3 Claims. (Cl. 274—21)

This invention relates to phonographs and more particularly to phonographs of the business type, commonly called dictating machines. Such phonographs or dictating machines when designed for use by a dictator are normally equipped with a suitable reproducing means as well as the usual recording means. By the inclusion of this reproducing means, it is possible for the user of such a machine to hear all, or a portion of, the material which has been recorded upon the record tablet at any time. It has been common practice to provide a sound box which may be conditioned for either recording or reproducing by the manipulation of a lever conveniently placed on the machine. This lever may have two or more positions in one of which the sound box is conditioned for recording and in another of which the sound box is conditioned for reproducing.

20 The use of the reproducing mechanism may be required when a dictator has been interrupted in the course of dictation. After such an interruption he may shift the control lever to a neutral position in which the styli of the sound box do not coat with the record, move the sound box backwardly along the record as far as necessary, and then move the control lever into the reproducing position wherein matter previously recorded will be reproduced as the sound box 25 moves forward up to the position which it occupied prior to the backward movement. When he has reached the end of the recorded matter and is again ready to dictate, it is necessary that he again manipulate the control lever to recondition the sound box for recording, whereupon he 30 may proceed with his dictation.

If it is desired to repeat only the last few words or portion of a sentence in order to pick up the train of thought, this may usually be done by 35 shifting the control lever directly from recording position to reproducing position without moving the sound box backwardly along the record. Reproduction of the last few words under such circumstances is obtained when the sound box is advanced over the record tablet by reason of the fact that the reproducing stylus in the sound box is offset a short distance behind the recording stylus, usually of the order of .1". When the control mechanism therefore is shifted from 40 recording to reproducing position without movement of the sound box relative to the record tablet, the reproducing stylus will engage the record tablet at a point several grooves behind the recording stylus so that as the sound box 45 is advanced along the record tablet the matter

recorded in these several grooves will be reproduced. This forms a convenient method of picking up the train of thought and obviously requires less manipulation than is necessary if the sound box proper is moved backwardly. However when the recorded matter of the last few grooves referred to has been reproduced it is again necessary to shift the control lever from the reproducing into the recording position before it is possible to proceed with dictation.

The manipulation required both prior to and subsequent to a reproduction of dictated matter is undesirable in such machines. Manipulations of this sort do not rapidly become automatic or instinctive with the user and they therefore have a tendency to distract and to break into the concentration normally required in dictation. For this reason it is desirable to make all operations automatic to as great an extent as possible.

The primary object of my invention therefore is to provide a business phonograph having a simple and improved means by which the phonograph may be quickly and easily shifted from recording position into reproducing position to subsequently repeat a portion of previously dictated matter.

Another object of my invention is to provide a construction by which the above means may be readily controlled from a point remote from the phonograph.

A further object of my invention is to provide means for automatically restoring the sound box to recording position after the reproduction of the matter last dictated on the record tablet.

Further objects and features of my invention will be disclosed in the following specification and appended claims.

For a clearer understanding of my invention, attention is directed to the drawings accompanying and forming part of this specification, where-in:

Figure 1 is a front elevation of a phonograph having a preferred embodiment of my invention applied thereto;

Fig. 2 is a top plan view partly broken away, of the phonograph of Fig. 1 and includes a schematic diagram of the electrical circuit for actuating and controlling the repeating mechanism;

Fig. 3 is an elevational view, partly in section, of the carriage and sound box of the phonograph of Fig. 1, as seen from the right;

Fig. 4 is a bottom plan view of the mechanism of Fig. 3;

Fig. 5 is a fragmentary view of the sound box.

and mechanism on the carriage when the sound box has been conditioned for reproducing;

Fig. 6 is a rear elevational view, partly broken away, of the carriage; and

Fig. 7 is a side view of the electro-magnet for actuating the repeating mechanism.

Referring to the drawings, the phonograph comprises a mandrel 1 supported on a shaft 2 journaled in a standard 3 projecting from a base 4. The mandrel is adapted to rotatably support a record tablet A. The mandrel driving means such as a motor (not shown) is connected to the mandrel through a belt 8 passing over a pulley 5. A suitable clutch mechanism 9-10 is provided for connecting or disconnecting the mandrel shaft and pulley 5. The base 4 carries two other standards 7 and 7' located near opposite ends of the base. These standards support a pair of guide rods 17-18 on which a carriage 13 is slidably mounted. The guide rods are supported in the standards by suitable means to prevent longitudinal movement thereof while permitting free rotation. A feed screw 20 is supported on a pair of pivots 20' mounted in the standards 7 and 7'. Rotation is imparted to the feed screw by a gear wheel 22 mounted on the mandrel shaft and meshing with a gear wheel 23 secured on the feed screw 20. A feed nut 21, mounted on a bracket 85 pivoted on a pin 85' in the carriage 13, is biased into engagement with the feed screw 20 by a coil spring 86 embracing a pin 87 which is threaded into the rear portion of the arm 13.

A sound box and the control mechanism therefor are mounted in the carriage and are well known in the art, being substantially the same as those described in detail in U. S. Patent No. 1,420,316, to N. H. Holland, entitled "Phonographs" and issued June 20, 1922. The sound box comprises a frame 32 having an upwardly extending neck 33 adapted to fit into an elbow 34 forming the inner end of a speaking tube comprising a flexible tube 35. The frame 32 also carries a downwardly extending lug 39 on which a casing 42 comprising a sound chamber is pivotally secured at 40. Connection between the sound chamber 42 and the neck 33 is made by a sliding tube 44. Casing 42 is closed by a diaphragm which carries a stirrup 55 at the lower end of which a recording stylus 56 is secured.

A floating weight 48 is likewise pivotally secured to the lug 39 and is positioned below the casing 42. A central hole is provided in the floating weight 48 through which the stirrup 55 may pass. A reproducing stylus arm 58 carrying a reproducing stylus 59 is pivotally secured by a pin 60 in a suitable slot in the floating weight 48. The end of the arm 58 opposite to that carrying the reproducing stylus lies at all times within the stirrup 55. The reproducing stylus 59 is positioned slightly behind the recording stylus with relation to the direction of advancing movement of the carriage. The floating weight 48 carries an advance ball 80, preferably made of sapphire and having a spherical end portion for coaction with the record, said ball having a diameter several times that of the recording or reproducing stylus.

The manual control mechanism for controlling the sound box at the arm or carriage 13 comprises a lever 65 pivotally mounted in the carriage about the front guide rod 17. The lever 65 has three positions in one of which the sound box is conditioned for recording, in another of which the sound box is conditioned for reproducing, and in the third of which the sound box

is moved to inoperative or neutral position and the feed nut 21 is simultaneously disengaged from feed screw 20. To accomplish the control of the sound box, the lever 65 actuates a pair of dogs 71 and 72 also mounted for rotary motion about the front guide rod 17. The dogs 71 and 72 coact respectively with lifting tabs 48' on the floating weight 48 and 42' on the casing 42. When the lever 65 is moved to its forward position in which the sound box is conditioned for recording, as shown in Fig. 3, both dogs 71 and 72 are rotated downwardly until they are entirely clear of the lifting tabs with which they cooperate so that both the floating weight and said casing are free to rotate in a clockwise direction. The floating weight will therefore move downwardly until the advance ball 80 comes into engagement with the record tablet A. At the same time the casing 42 will likewise rotate downwardly, the stylus 56 and the stirrup 55 passing through the opening in the floating weight, until the recording stylus 56 likewise engages the record tablet A. It will be noted that the advance ball 80 is positioned slightly in advance of the recording stylus 56 lengthwise of the record tablet so that when the mandrel is rotated, the recording stylus will cut a groove in the record material independently of the floating weight, the floating weight being merely carried along supported by sliding contact of the advance ball and the uncut portion of the record tablet, in advance of the recording stylus. The floating weight is not used in the operation of recording and is by this means merely maintained in a position in which it does not interfere with the recording stylus.

When the control lever 65 is moved into its central or neutral position, both dogs 71 and 72 are rotated in a clockwise direction and coact with their respective lifting tabs 42' and 48' to rotate the casing 42 and the floating weight 48 upwardly to a position in which both the recording and reproducing styli and the advance ball are entirely clear of the record tablet A. At the same time a roller 84' coacts with the head 84 of a plunger 81 slidably mounted in the carriage 13. The plunger 81 moves backwardly in engagement with the bracket 85 and thereby moves said bracket and the feed nut 21 against the pressure of the spring 86 to a position in which the feed nut is clear of the feed screw 20 whereupon the carriage may be freely slid along the guide rods. When lever 65 is in any other position than neutral, roller 84' is moved out of contact with the plunger, thus allowing spring 86 to move feed nut 21 into engagement with feed screw 20.

When the control lever 65 is moved to its rear or reproducing position the dog 72 is maintained in its uppermost position in which it holds the casing 42 adjacent the frame 32. However, the dog 71 is then rotated downwardly and allows the floating weight to move downwardly. Since the rear portion of the reproducing stylus arm 58 lies at all times within the stirrup 55 which is held up with the casing 42, the downward motion of the floating weight 48 will impart a counter-clockwise rotation to the reproducing stylus arm 58 which will cause the reproducing stylus 59 to engage the record tablet before the advance ball 80 engages it. By reason of the offset of the recording and reproducing styli, the reproducing stylus engages the record behind the recording stylus relative to the advancing direction of movement of the carriage. Under these conditions the floating weight 48 serves to bias the reproducing stylus 59 into engagement with the record and

also serves to bias the other end of the reproducing stylus arm 58 into engagement with the bottom of the stirrup 55. If, therefore, a vibratory motion is applied to the stylus 59 by the record groove of tablet A when the latter is rotated, such vibratory movement will also be imparted to the stirrup 55 and consequently to the diaphragm which will emit sounds in the well known manner. The mechanism by which the prescribed movements of the dogs 71 and 72 are obtained as a result of movement of the control lever 65 is substantially the same as that described in detail in the Holland patent mentioned above and will not be repeated herein. All of the mechanism described so far is well known in the art and is in common use on commercial phonographs intended for manual control.

It will be noted that the only motion required to change the sound box from its recording position to its reproducing position is the raising of the casing 42 which disengages the recording stylus, disengages the advance ball 80, and engages the reproducing stylus 59. In providing a remotely controllable mechanism for shifting the sound box from its recording to reproducing position therefore, an auxiliary lifting dog 95 is pivotally mounted about the guide rod 17 adjacent the lifting dog 72 and is freely rotatable independently thereof. The lifting dog 95 is provided with a nose 95' for coaction with the lifting tab 42' on the casing 42. The lifting dog 95 is also provided with a shoulder to coact with a pin 98 which is secured in a disc 97 mounted for free rotation about the guide rod 17 within a boss 15 of the carriage 13. A coil spring 102 connected to the disc 97 and to the side wall of the boss 15 serves to urge the disc 97 in a counterclockwise direction when the carriage is viewed from the right hand side as in Figs. 3 and 5. This tends to move the pin 98 away from the shoulder on the lifting dog 95 and to allow the latter to fall to a point in which its nose 95' is entirely below and clear of the lifting tab 42'. One end of a connecting rod 99 embraces the pin 98 and is free to rotate thereon. The connecting rod 99 passes toward the rear of the carriage and is supported in a suitably drilled hole in a bracket 100 secured on the side of the carriage 13 by suitable screws. The rear end of the connecting rod 99 is adapted under certain conditions to contact with a spring 101' mounted on a rocking member 101. The rocking member 101 is pinned to a short shaft 103 which is journaled in the bracket 100 and in the adjacent side wall of the carriage 13 and is held against longitudinal movement by a pair of collars 106 and 106' pinned thereon. A cam 118 is splined on the back rod 18 by a pin 18' and moves with the carriage by reason of its confinement between the bracket 100 and the adjacent side wall of the carriage 13. The cam 118 is adapted to coact with the rocking member 101. If the back rod 18 is given a clockwise rocking motion with the machine in condition for recording, the cam 118 will contact with the rocking arm 101 and will cause it to be rotated forwardly. As a result of such rotation the spring 101' will strike the rear end of connecting rod 99 and move it forwardly. Forward movement of the connecting rod 99 causes the pin 98 also to be moved forwardly against the urging of spring 102, to coact with the shoulder on the lifting dog 95, thereby turning said dog so that the nose 95' thereof is raised to coact with the lifting tab 42' on the casing 42. The casing 42 is thus rotated upwardly, disengaging the recording stylus and

the advance ball from the record tablet and engaging the reproducing stylus 59, thereby conditioning the mechanism for reproduction.

The means which causes the necessary rotation of the back rod 18 to start the operation just described comprises an electro-magnet 110 having a core 113 and a U-shaped armature 111 pivoted at 112. A link 116 is pivotally mounted on one side of the armature 111 and passes upwardly to a pivotal connection with an arm 117 secured to the back rod 18. A simple switch 115 may be provided at any desired remote point, said switch being connected in series with conductors 114, a battery 114', and the coil of the electro-magnet 110. The armature 111 is normally biased by gravity to its lowermost position as shown in Fig. 7. However when switch 115 is closed, thus causing current to flow in the electro-magnet 110, the armature 111 is attracted upwardly opposite the core 113 of the electro-magnet and by reason of its connection through the link 116 and the arm 117, to the back rod 18, it imparts a rocking movement to the back rod and thereby conditions the sound box for reproducing in the manner already described.

It will be noted that, with the construction already described, as soon as the switch 115 is opened and the electro-magnet 110 thereby de-energized, the sound box will tend to return immediately to its recording position by reason of the movement of pin 98 away from the shoulder on the lifting dog 95, under the influence of the spring 102. In order to maintain the sound box in reproducing position the connecting rod 99 is provided with a notch 99' into which a pawl 119 may fall when the connecting rod 99 is moved forward. The pawl 119 is pivoted on the bracket 100 and is urged into engagement with the connecting rod 99 by a coil spring 119' embracing the pivot screw 121 on which the pawl is mounted.

The mechanism described above will upon closure of the switch 115 therefore condition the sound box for reproducing and maintain it in reproducing position so that as the carriage is moved forward the matter recorded in the space 45 on the cylinder corresponding to the offset between the recording stylus 56 and the reproducing stylus 59 will be reproduced. However in order to make the device entirely automatic it is necessary that the sound box be reconditioned for recording when the matter recorded has been entirely reproduced. In order to accomplish this the pawl 119 is provided with a curved downwardly extending arm 122 terminating in a bent lug carrying a screw 123. A marker plate 124 is provided adjacent to the carriage on its advancing side. The marker plate 124 is provided with an enlarged collar 125 embracing the back rod 18 and having an adjustable spring and plunger mounted in a suitable well 126 therein to provide a frictional engagement with the back rod. The marker plate 124 is provided with a forwardly extending portion 133 for coaction with the screw 123 in the lower end of the pawl extension 122. The plate 124 is carried along in advance of the carriage 13 by contact with the side wall thereof during normal dictation. The pin 123 is adjusted so that, while the plate 124 is in contact with the adjacent side wall of the carriage 13, it holds the pawl extension 122 in a position where the pawl 119 is out of engagement with the connecting rod 99. It will be seen that as long as the plate 124 is in contact with the said side wall of the carriage 13, the pawl 119 will remain in inoperative position and will be ineffective for maintaining

the sound box in reproducing condition when it is moved thereto by forward motion of the connecting rod 99. Mechanism is therefore provided to move the marker plate 124 a slight distance in 5 advance of the carriage whenever the sound box is conditioned for reproducing by actuation of the control switch 115. This mechanism comprises a cup-shaped member 132 embracing the shaft 103 and extending through an opening in 10 one side wall of carriage 13. The outer end of the cup-shaped member 132 is partially cut away to provide a shoulder 133' which coacts with the marker plate 124 and thus prevents rotational movement of the cup-shaped member 132. The 15 bottom of the shouldered portion 133' of the cup-shaped member 132 abuts the marker plate 124. The marker plate 124 is held against rotary movement by a shoulder screw 135 which passes through the marker plate and is threaded into 20 the carriage 13. The cup-shaped member 132 is provided with a slanting slot 131 with which a pin 130 secured in the shaft 103 coacts. When the back rod 18 is rotated causing cam 118 to 25 coact with the rocking member 101 and thus move it forwardly and at the same time rock the shaft 103, the pin 130 will move along the slot 131 and cause the cup-shaped member 132 to be moved outwardly thus giving advance spacing movement 30 to the marker plate 124. Under these circumstances the pawl 119 is free to rotate under the urging of the spring 119' and as the connecting rod 99 is moved forwardly the said pawl drops into the notch 99' thus maintaining the sound 35 box in reproducing condition. The advance spacing movement imparted to the marker plate 124 is approximately equal to the offset of the recording and reproducing styli.

The operation of the device is as follows: When it is desired to dictate, the control lever 65 is 40 moved to its forward or dictating position wherein the recording stylus engages the record. When the mandrel is revolved, the carriage is moved forward by the cooperation of the feed screw 20 and the feed nut 21 and a groove is cut in the 45 record. If it is desired to repeat the last few words which have been dictated, the control switch 115 is closed thus energizing the electromagnet 110 and imparting a rocking movement to the back rod 18. Such rocking movement of 50 the back rod 18 causes the cam 118 to be rotated which in turn moves the rocking member 101 forward to contact the connecting rod 99 and move the dog 95 upwardly, thus raising the casing 42 and conditioning the sound box for reproducing. 55 At the same time the cup-shaped member 132 is moved outwardly thus moving the marker plate 124 to a position slightly in advance of the carriage and out of contact with the screw 123 on the pawl extension 122 so that the pawl 119 will 60 fall into the notch 99' in the connecting rod 99 and thus maintain the sound box in the reproducing position. When the mandrel is again rotated the last few words dictated will be reproduced by reason of the offset between the recording and reproducing styli. When the carriage 65 has moved a distance approximately equal to the offset between the styli and has reproduced the last of the recorded matter, the screw 123 will again contact the marker plate 124 thus

withdrawing the pawl 119 from the notch 99' and allowing the connecting rod 99 to be moved backwardly by action of the coil spring 102. The casing 42 will thereupon move downwardly under the action of gravity and the sound box will thereby be automatically reconditioned for recording. The dictator may then proceed with his dictation, the only manipulation required of him in order to repeat the last few dictated words having been a single momentary closure of the 10 switch 115, whereupon as has been described above, the sound box is conditioned for reproducing, and, when the last of the recorded matter has been reproduced, is automatically reconditioned for recording. 15

Having thus described my invention, I claim:

1. In a phonograph, a sound box movable with respect to a record tablet and comprising a recording stylus and a reproducing stylus alternatively shiftable into record engaging position, 20 said reproducing stylus being offset to engage the record at a point rearwardly of said recording stylus with respect to the forward movement of the sound box, a manual control on the phonograph for effecting shifting of said recording 25 stylus into record engaging position, a remote control and a mechanism operable by said remote control independently of said manual control for effecting engagement of said reproducing stylus with the record tablet for a predetermined 30 amount of forward movement of said sound box substantially equal to the amount said reproducing stylus is offset.

2. In a phonograph, a sound box comprising a recording stylus normally biased into record engaging position and a reproducing stylus normally out of record engaging position and offset behind said recording stylus with reference to the normal direction of movement of said sound box when recording, means for imparting an advance 40 movement to said sound box with respect to a record tablet carried by said phonograph, mechanism operable at will for effecting shifting of said recording stylus out of and said reproducing stylus into record engaging position at any time 45 during an advanced movement of said sound box, means for maintaining said reproducing stylus in record engaging position after operation of said mechanism, and a device movable relatively to said sound box which when in a certain position 50 relative to the sound box renders said means inoperative.

3. In a phonograph, a rotatable mandrel adapted to carry a record tablet, a sound-box associated with said tablet and normally conditioned for recording and comprising a recording stylus and a reproducing stylus, said reproducing stylus being offset behind said recording stylus with reference to an advancing movement of said sound-box with respect to said tablet, 60 means for imparting such an advancing movement to said sound box, mechanism, operable by remote control at any time while said sound-box is advancing, for conditioning said sound box for reproducing, a remote control for operating said mechanism and a device which automatically restores said sound-box to recording condition after a predetermined interval of reproducing. 65

HEINRICH F. MAX GRAMANN.
